WIRE TIGHTENER AND TWISTER FOR
CONCRETE FORMS

Edward J. Duffaghan, Boise, Idaho

Application January 19, 1948, Serial No. 3,024

7 Claims. (Cl. 146—118)

1

This invention relates to a wire pulling and tying device and is more particularly designed for tightening and tying concrete form tie wires.

The principal object of the invention is to provide a highly efficient device which will draw the wires to any desired degree of tension and which will form a tying twist therein without danger of twisting off or "burning" off the wire.

Other objects and advantages reside in the detail construction of the invention, which is designed for simplicity, economy, and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a fragmentary view illustrating a typical concrete wall form illustrating the invention in place thereon;

Fig. 2 is a detail view illustrating the type of wire tie formed by the device;

Fig. 3 is an enlarged side view of the improved wire tying jack;

Fig. 4 is a plan view thereof illustrating it in the process of forming the preliminary turn for a wire tie;

Fig. 5 is a longitudinal section taken on the line 5—5, Fig. 3, illustrating the tool in the process of completing the wire tie; and

Fig. 6 is an enlarged section through the tying point of the improved jack taken on the line 6—6, Fig. 4.

In Fig. 1 the side forms of a typical concrete wall form is indicated at 10 with its vertical struts at 11 and spacers at 12. The struts are held together against the spacers by means of a tie wire 13. The wire is passed between the boards of the form and around the struts 11. The two extremities are twisted into a tying twist.

This invention is designed for applying tension to the wire 13 and forming the tying twist in the wire.

The improved jack consists of a jack bar 14 having ratchet teeth 15 formed in one of its edges. One extremity of the bar 14 is provided with a wire twisting head 16.

The main frame is slidably mounted on the jack bar 14. An operating lever 18 is hingedly mounted on a lever pin 19 extending through a pair of arms 20 from the main frame 17. The side arms 20 terminate in a receiving socket 43 for receiving a holding bar 44. A ratchet dog 21

is mounted on a ratchet pin 22 extending through the arms 18. The extremity of the dog 21 successively engages the ratchet teeth 15 as the levers 18 are swung back and forth.

5 The operating levers are provided with a receiving socket 23 for receiving a jack handle 24. A holding dog 25 is mounted upon a pin extending across the main frame. The dog 25 is lifted by means of a connecting link 26 connected at one 10 extremity to the dog 21 by means of a pin 27. The link 26 is provided at its other extremity with an elongated slot 28 which rides upon a pin 29 in the holding dog 25. The dog 21 is constantly urged toward the teeth 15 by means of a spring plunger 30 and the dog 25 is similarly urged by means of a second spring plunger 31.

At each outward stroke of the operating levers 18 the ratchet dog 21 travels outwardly along the teeth 15. As it approaches the outward limit of its travel the pin 29 will reach the extremity of the slot 28 lifting the holding dog. At each inward stroke the dog will push the frame 17 outwardly.

A floating frame 32 is also slidably mounted on the jack bar 14 and connected to the main frame 17 at each side by means of two toggle links 33 and 49. The two toggle links 33 are connected together by means of a cross-piece 34. Each link 33 is provided with a locking tooth 45 positioned to engage a locking latch 46. A tension spring 35 extends from a spring socket in the main frame 17 into a similar spring socket in the floating frame 32 terminating at its extremity in spring pins 36. The floating frame 32 is provided at 30 each side with a stationary vise block 37.

A gripping cam 38 acts against each vise block 37 to grip the extremity of the wire 13 in place. The gripping cams 38 are provided with vise handles 39 for clamping them against the wire and are provided with releasing arms 40.

The twisting head is formed with a laterally extending wire receiving notch 41 having an arcuately curved bottom as shown in Fig. 6. A winding pin 42 is inserted in the bottom at the high point thereof and projects outwardly to form a tapered wire winding post.

The operation of the jack is as follows: the wire 13 is passed through the two forms 10 and around the far strut 11. The two extremities of the wire are brought out on each side of the near strut 11 and through the sides of the wire receiving slot 49. They are then passed against the vise blocks 37 and clamped against these blocks by means of the handles 39. The jack handle 24 is then reciprocated with one hand while the jack is supported

with the other hand on the arm 44. This causes the frame 17 to travel outwardly along the ratchet bar 14. Its outward movement is communicated to the floating frame 32 by the toggle links 33, since they are locked by means of the locking tooth 45 and the locking latch 46.

When the desired tension has been placed in the wire the entire tool is rotated around the winding point 42 for approximately one-half a revolution. This hooks the two extremities of the wire 13 together. The latch 46 is now released, freeing the floating frame 32 from the main frame 17 and the tool is rotated for five or six additional turns. This rotation winds the two wires around the pin 42 in a conical wind or helix such as shown in Fig. 2.

The wire required to form the helix is obtained by the sliding action of the floating frame 32 toward the twisting head 16 under the tension of the spring 35. This keeps sufficient tension on the wire to form a perfect wind but allows the wire sufficient freedom so that it will not be twisted or broken in forming the wind.

The releasing arms 40 act as safeties, that is, should the wire be too short or should the head be revolved too many times these arms will contact the head 16 releasing the gripping cams 38 from the wire.

The gripping faces of the cams 38 are preferably roughened as shown in broken line at 47, to obtain a better grip upon the wire and these cams are provided with side flanges 48 which prevent the wire from slipping from the vise blocks 37.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A device for tightening and tying concrete form tie wires comprising: a jack bar; a main frame arranged to travel along said jack bar; means for imparting traveling movement to said main frame; a floating frame arranged to travel along said jack bar; a tension spring connecting said floating frame to said main frame; wire clamping means on said floating frame for securing the extremities of a wire thereto; a winding pin projecting from the extremity of said jack bar adjacent said floating frame; and means for rotating said jack bar to wind the extremities of said wire about said pin under the tension of said springs.

2. A device for tightening and tying concrete form tie wires comprising: a jack bar; a main frame arranged to travel along said jack bar; means for imparting traveling movement to said main frame; a floating frame arranged to travel along said jack bar; a tension spring connecting said floating frame to said main frame; wire clamping means on said floating frame for securing the extremities of a wire thereto; a winding pin projecting from the extremity of said jack bar adjacent said floating frame; and means for rotating said jack bar to wind the extremities of said wire about said pin under the tension of said springs; a pair of hinged toggle links movably connecting said floating frame to said main frame during the winding operation and acting to limit the total separation between said two frames; and latch means engaging said links to lock them in the folded

position for locking said floating frame to said main frame during the tightening operation.

3. A device for tightening and tying concrete form tie wires comprising: a jack bar; a main frame arranged to travel along said jack bar; means for imparting traveling movement to said main frame; a floating frame arranged to travel along said jack bar; a tension spring connecting said floating frame to said main frame; wire clamping means on said floating frame for securing the extremities of a wire thereto; and a tying head on the extremity of said jack bar adopted to contact the concrete form structure, said tying head having a wire groove across its face through which said wire extremities pass to said clamping means; means for rotating said jack bar, said frames, and said tying head as a unit to wind the extremities of said wire together under the tension of said springs; and releasable means rigidly connecting said floating frame to said main frame during the winding operation.

4. A device for tightening and tying concrete form tie wires comprising: a jack bar; a main frame arranged to travel along said jack bar; means for imparting traveling movement to said main frame; a floating frame arranged to travel along said jack bar; a tension spring connecting said floating frame to said main frame; wire clamping means on said floating frame for securing the extremities of a wire thereto; a tying head on the extremity of said jack bar adopted to contact the concrete form structure, said tying head having a wire groove across its face through which said wire extremities pass to said clamping means; means for rotating said jack bar, said frames, and said tying head as a unit to wind the extremities of said wire together under the tension of said springs; and releasable means rigidly connecting said floating frame to said main frame during the winding operation; and a tapered winding point inset in said head at the mid-point of said groove to form an axis about which said wires will wind when said head is rotated, said floating frame being free to move away from said main frame under the tension of said springs as said wire is wound to allow winding slack therein.

5. A device for tightening and tying concrete form tie wires comprising: a jack bar; a main frame arranged to travel along said jack bar; means for imparting traveling movement to said main frame; a floating frame arranged to travel along said jack bar; resilient means connecting said floating frame to said main frame and acting to pull the former toward the latter; wire clamping means on said floating frame for securing the extremities of a wire thereto; a tying head on the extremity of said jack bar adopted to contact the concrete form structure, said tying head having a wire groove across its face through which said wire extremities pass to said clamping means; and releasing arms projecting from said wire clamping means and positioned to contact said tying head to release said clamping means at a predetermined point.

6. A device for tightening and tying concrete form tie wires comprising: a jack bar; a main frame arranged to travel along said jack bar; an operating lever hinged on said frame; a ratchet dog carried by said operating lever so as to successively engage ratchet teeth formed on said jack bar as said ratchet lever is reciprocated to impart a traveling movement to said main frame; a holding dog mounted on said frame and successively engaging said teeth to prevent re-

turn movement of said main frame; a winding head on the extremity of said jack bar adapted to contact a concrete form structure; a wire groove across said winding head for receiving the extremities of a tie wire; a winding point projecting from said head at the middle of said groove about which said extremities will wind when said head is rotated; a floating frame slidably mounted on said jack bar between said main frame and said head; a tension spring connecting said floating frame to said main frame so as to allow the former to be drawn away from the latter under the tension of said spring; means on said floating frame for securing the extremities of said tie wire thereto; and releasable means for fixedly latching said floating frame to said main frame when desired.

7. In a wire tightening tool for tightening the tie wires of concrete forms, means for winding the extremities of said tie wires together comprising: a winding head; a groove extending across the face of and upwardly along the two sides of said head in which the extremities of said wire are received so that rotation of said

head will twist said two extremities about each other; movable means holding the extremities of said wire; and a spring connected with said movable means and normally urging the latter away from said head so as to allow said movable means to move toward said head as said wire is wound about said winding point; and means for rotating said winding head and said movable means so as to wind said wire about said point.
